UNITED STATES PATENT OFFICE.

ISAAC R. CONCOFF AND ROBERT SIMON LOVETT, OF PORTLAND, OREGON.

LADDER.

No. 926,642.

Specification of Letters Patent.

Patented June 29, 1909.

Application filed December 5, 1907. Serial No. 405,271.

To all whom it may concern:

Be it known that we, ISAAC R. CONCOFF and ROBERT SIMON LOVETT, citizens of the United States, and residents of Portland, in the county of Multnomah and State of Oregon, have invented a new and Improved Ladder, of which the following is a full, clear, and exact description.

This invention is an improved ladder especially designed for use by firemen, it being capable of considerable and rapid extension, adapting it for use in connection with tall buildings.

One embodiment of the invention consists of a ladder composed of a series of sections of varying widths telescoped one within the other and a gear mechanism for driving the several sections, causing them to simultaneously move with respect to each other. The central section of the ladder, which is the upper section when extended, is provided with a pivotal extension capable of being thrown to a horizontal position to engage the roof of a building and rigidly hold the upper end of the ladder in position. A flexible line is connected to the pivotal extension and is wound about an automatically driven drum, said line being engaged when the ladder is extended, by a bracket and forming a truss, thereby materially increasing the strength.

Reference is to be had to the accompanying drawings forming a part of this specification, in which similar characters of reference indicate corresponding parts in all the figures.

Figure 1 is a front elevation of the ladder complete with the several sections thereof telescoped together, as when the ladder is not in use; Fig. 2 is a side elevation of the ladder as shown in Fig. 1; Fig. 3 is a front elevation of the three upper sections of the ladder when extended; Fig. 4 is a side elevation of the construction shown in Fig. 3; Fig. 5 is a skeleton view of the operating mechanism with the several sections of the ladder removed; Fig. 6 is a side elevation of the construction shown in Fig. 5; Fig. 7 is an end view of an angular metal plate which is used in holding the several sections of the ladder in sliding engagement; Fig. 8 is an edge view of the same; Fig. 9 is a cross section on the line 9—9 of Fig. 1 looking in the direction of the arrow, and Fig. 10 is a like section on the line 10—10 of Fig. 1 looking in the direction of the arrow.

The ladder is made up of any desired num-

ber of sections, that being shown being four in number, designated respectively, by the numerals 1, 2, 3, and 4, successively increasing in width and telescoped one within the other. The bottom or wide section 1 of the ladder is at all times stationary and is fixed at its lower end to a base-plate 5, as best shown in Figs. 1, 2, 5 and 6.

Journaled in the upper end of the base-plate 5 is a horizontal shaft 6, having fixed to its inner end a beveled gear 7, the latter being in mesh with a somewhat smaller beveled gear 8 fixed to the lower end of a vertical shaft 9. To the upper end of the shaft 9 is fixed a sprocket-wheel 10 which acts to drive a chain 11 passing about sprocket-wheels 12 fixed to the lower end of long, vertical shafts 13, the latter being journaled in suitable bearings carried by the side bars of the section 1. At the upper extremities of the shafts 13 are fixed worm gears 14 and which mesh with worm racks 15 secured to the rear face of each of the side bars of the section 2, said worm racks extending, as shown in dotted outline in Fig. 2, the entire length of this section.

Journaled in the lower end of the section 2 is a transverse shaft 16 having fixed to each of its ends a gear 17 which are in mesh with rack bars 18 secured to the top faces of the side bars of section 1. Also fixed to the shaft 16 intermediate the gears 17, is a sprocket-wheel 19 connected to a sprocket-wheel 20 by a chain 21, said sprocket-wheel 20 being fixed to a shaft 22 journaled at each end in the upper end of the section 2. Also fixed to the shaft 22 near its ends, are gears 23 in mesh with rack bars 24 secured to the rear faces of the side bars of the section 3.

Journaled in the lower end of the section 3 is a transverse shaft 25 having fixed to each of its ends a gear 26 in mesh with rack bars 27 secured to the upper faces of the side bars of the section 2 and corresponding with the rack bars 18 secured to the side bars of the section 1. Also secured to the shaft 25 intermediate the gears 26, is a sprocket-wheel 28 connected with a sprocket-wheel 29 by a chain 30. The sprocket-wheel 29 is fixed to a short shaft 31 journaled in the section 3 and also having fixed thereto adjacent to the sprocket-wheel 29 a gear 32 in mesh with a rack bar 33 fixed to the rear face of one of the side bars of the section 4 and corresponding in construction to the

rack bars 24 carried by the section 3. We have shown rack bars fixed to the upper face of the section 3 which, in the present construction, have no function but are for the purpose of serving in the same capacity as the rack bars 18 and 33 should another section of the ladder be added.

The guide-plate, as shown in Figs. 7 and 8, is employed for maintaining the several sections of the ladder in sliding engagement, said plate being bent at one end to provide a flange 34, and at its opposite end in the reverse direction to provide a flange 35, this latter flange being bent to form a channel 36 intermediate its length for receiving the racks when applied to the ladder sections. The application of these guide-plates to the ladder is illustrated in Fig. 1, in which the flanges 34 of the guide plates are secured to the lower ends of the side bars of the sections 2, 3 and 4, leaving the flanges 35 to respectively project over the side bars of the sections 1, 2 and 3. At the upper ends of the ladder sections the guide-plates are secured in reverse order, the flanges 34 of the plates being fixed to the bottom faces of the side bars of the sections 1, 2 and 3 with the flanges 35, respectively, projecting over the top faces of the side bars of the sections 2, 3 and 4. It is thus seen by this arrangement that the several sections of the ladder are at all times maintained in sliding engagement and cannot be laterally separated.

The central section 4 of the ladder is provided with an extension 37 having hooked over extremities 38 and pivotally connected to the section 4 on a pin 39. As best shown in Figs. 3 and 4, the side bars of the extension 37 are diminished in width and thickness and fit into corresponding cut-out portions into the side bars of the section 4 when in vertical alinement therewith. Secured to each side of the section 4 adjacent to the extension 37 are curved brackets 40, each being provided with a slot 41 of substantially 90 degrees in length concentrically arranged to the pin 39. In these slots project pins 42 extending from the side bars of the extension 37. By this construction it is apparent that the extension may be thrown to a horizontal position and will be held from further movement by reason of the pins 42 contacting with the upper ends of the slots 41.

Pivoted between the side bars of the section 2 substantially midway of their length, is a bracket 43 best shown in Figs. 1 and 4 and is concave on its outer face with a notch 44 centrally arranged therein. This bracket is normally forced outwardly by a spring 45 secured to one of the side bars of the section 2 and when in a horizontal position engages a line 46 in its notch 44, said line being connected at its upper end to the extension 37 and at its lower end to a drum 47, the latter

being carried by a shaft 48 journaled in the upper end of a standard 49 pivoted at 50 to one side of the base-plate 5. The shaft 48 has also fixed thereto an operating hand-wheel 51 and at the opposite side of the drum 47 a friction-wheel 51^a frictionally engaging the rear, beveled edge of the beveled gear 7.

The operation of the ladder is as follows: On driving the shaft 6 from any suitable source of power, the vertical shafts 13 and worms 14 carried thereby are caused to revolve through the intermediate gearing; and since the worms 14 mesh with the worm racks 15 secured to the section 2, this section 70 is moved upwardly. As the section 2 moves upwardly it revolves the gears 17 fixed to the shaft 16 journaled in its lower end. This shaft in turn, drives the gears 23 at the end of the shaft 22 through the sprocket-wheels 85 19 and 20 and the connecting chain 21. As the gears 23 revolve, they move the section 3 upwardly with respect to the section 2, by reason of being intermeshed with the rack-bars 24 carried by the section 3. As the section 3 moves upwardly with respect to the section 2, the gears 26 fixed to the shaft 25 journaled at the lower end of this section, are caused to revolve by reason of being intermeshed with the rack-bars secured to the 95 front face of the side bars of the section 2. This drives the short shaft 31 and the gear 32 fixed thereto, journaled in the upper end of the section 3, through the intermediate sprocket-wheels 28 and 29 and their connecting chain 30, causing the section 4 to move upwardly with respect to the section 3 by reason of the gear 32 being intermeshed with the rack-bar 33 secured to its rear face. As the sections of the ladder move upwardly, 100 the line 46 is unreeled from the drum 47 by reason of the frictional engagement of the friction-wheel with the rear face of the gear 7; and when the sections have been extended for one-half their length, the bracket 43 is 110 automatically thrown outward by the spring 45, said bracket being maintained in a vertical position up to this time by the rounds of the section 1. As the bracket is thrown outwardly its convex outer face carries the 115 line 46 to its central notch 44. To adjust the tension on the line after the ladder is extended, the standard 49 is thrown rearwardly on its pivot 50 to disengage the friction-wheel with the beveled gear 7, and may 120 be held in this position by a latch 52 while the hand-wheel 51 is operated, as shown in dotted outline in Fig. 6. This latch is pivotally connected to the base-block 5 and has a notch in its free end to engage with a pin 125 53 projecting from one side of the standard 49. It is thus seen that all of the sections of the ladder are moved simultaneously with respect to each other in the same direction as the shaft 6 is driven; also the line 46 130

at the same time is automatically unwound or wound on the drum 47, depending on the direction in which the shaft 6 is driven.

It should be noted that the extension 37 5 can be pulled to the horizontal position by the line 46; also that the bracket 43 engaging said line will be automatically swung on its pivot as the ladder is extended and brought back to normal position when telescoped together. Further, the guide-plates will not only prevent the several sections of the ladder from being separated but will also act as stops when the sections have been extended to their limit.

15 The invention has been described in detail in order that the construction and operation might be fully understood. The precise embodiment, however, is not material provided the essential characteristics are employed as 20 pointed out in the annexed claims.

Having thus described our invention we claim as new and desire to secure by Letters Patent:

1. A plurality of ladder sections telescoped one within the other comprising an outer section, an inner section, and intermediate sections, a rack fixed on one side of the outer section, a rack fixed on the opposite side of the inner section, racks fixed on both sides of 30 the intermediate sections, gearing carried by the several sections intermeshing with the racks, and means for driving said gearing to cause all of said sections but the outer section to move simultaneously in one direction.

35 2. A ladder composed of a plurality of sections telescoped one within the other, means to extend said sections with respect to each other, a tension member at the rear of the ladder section, and a strut automatically 40 erected and clasped at the rear of the ladder when the ladder sections are extended and retracted.

3. A ladder composed of a plurality of sections telescoped one within the other, a line 45 connected to the inner section near its upper end, a drum on which the line is connected at its opposite end, a bracket connected to one of the sections forming a truss in connection with the line, means for driving the drum and 50 moving all but the outer of the ladder sections with respect to each other, and means for automatically projecting and retracting the bracket by the actuation of the first mentioned means.

55 4. A ladder composed of a plurality of sections telescoped one within the other, rack bars fixed to both the front and rear sides of certain of said sections, gearing intermeshing with the rack bars, and means including the 60 rack bars for driving said gearing to cause all of said sections but the outer section to move simultaneously in one direction.

5. A ladder composed of a plurality of sections telescoped one within the other, means

for causing all of said sections but the outer 65 section to move simultaneously with respect to each other in the same direction, a bracket pivotally connected to one of said sections automatically projected and retracted by the operation of said means, and a line disconnected from the bracket and connected to another of said sections automatically engaged by the bracket to form a truss when the sections are extended.

6. A ladder composed of a plurality of sections telescoped one within the other, a rack fixed to one side of the outer section, a rack fixed to the opposite side of the next adjacent and second section, a worm in mesh with the last mentioned rack for moving all 80 of the sections with respect to the outer section, and a gear journaled on said next adjacent section in mesh with the first mentioned rack for moving the third section with respect to the second section. 85

7. A ladder composed of a plurality of sections telescoped one within the other, a rack fixed to one side of the outer section, a rack fixed to the opposite side of the third section, a rack fixed to one side of the intermediate 90 section, a vertical shaft having a worm wheel in mesh with the rack of the intermediate section, a gear journaled on the lower portion of the intermediate section in mesh with the rack fixed to the outer section, a gear 95 journaled on the upper portion of the intermediate section in mesh with the rack of the third section, means for driving the last mentioned gear from the first mentioned gear, and means for driving said shaft, whereby 100 all of said sections but the outer section are caused to move simultaneously with respect to each other.

8. A ladder composed of a plurality of sections telescoped one within the other, a 105 bracket pivotally supported on the rear side of one of the intermediate sections of the ladder and foldable to the side thereof by the contraction of the ladder, a spring for projecting the bracket when the sections of the 110 ladder are extended, and a line attached to the inner section of the ladder automatically engaging the bracket to provide a truss when the several ladder sections are extended.

In testimony whereof we have each signed 115 our name to this specification in the presence of two subscribing witnesses.
